UNITED STATES PATENT OFFICE.

ROBERT D. HAYES, OF NEW HAVEN, CONNECTICUT, ASSIGNOR TO INDEX VISIBLE,
INCORPORATED, OF NEW HAVEN, CONNECTICUT, A CORPORATION OF NEW YORK.

INDEX OR FILE.

1,328,956.

Specification of Letters Patent. Patented Jan. 27, 1920.

Application filed July 31, 1917. Serial No. 183,769.

To all whom it may concern:

Be it known that I, ROBERT D. HAYES, a citizen of the United States, residing in the city and county of New Haven and State 5 of Connecticut, have invented certain new and useful Improvements in Indexes or Files, of which the following is a full, clear, and exact description.

This invention relates to indexes or files, 10 and it has particular reference to a so-called visible index embodying a plurality of record holding members or cards which, in the normal position, are held in overlapped relation so that only the marginal portions 15 thereof are exposed to view. The invention also has special reference to a system of this kind in which each card is held flatwise on a support by a tongue or tongues on the card, as shown, for example, in the Fisher 20 Patent No. 1,048,056, dated December 24, 1912, although it may be used to advantage in connection with other record systems.

One of the primary objects of the present invention is to provide improved means for 25 protecting the free edges of the cards and the record matter carried thereon where the index is used in a machine shop or other establishment in which the cards are handled by persons having oily or dirty fingers. 30 More particularly, it is aimed to furnish an index or file wherein record matter, written or typewritten along or near the edge portion of a card, is protected in an extremely simple and economical way by a covering of 35 suitable transparent oilproof and water- proof material. In the embodiment of my invention selected for illustration, the cards are of what is called the downhanging type, 40 their upper portions being secured detach- ably to a suitable support and their lower free edge portions carrying the record matter, and in this case the transparent covering for each card is located at or near the lower edge portion thereof. However, the 45 invention is equally applicable to a card system in which the cards are of the upstanding type, *i. e.* where the record matter is written or typewritten along the upper edges, or otherwise carried by the upper 50 edge portions of the cards.

My invention also has in view the provision of an index or file composed of a plurality of overlapping cards, wherein the

transparent protective covering for the visible marginal portion of each card is carried 55 by the card in front of the first mentioned card. This permits the construction to be of a very simple character, because it is merely necessary to paste, or otherwise secure, a strip of celestron, or other transparent material, along the edge of each card in such a manner that it will extend beyond the edge of the card proper and overlie the exposed edge portion of the card behind, on which exposed edge portion the record matter 60 is usually typewritten or written directly. It is, of course, feasible, however, to cover intermediate record slips or inserts in this same manner.

To these and other ends, the invention 70 consists in the novel features and combinations of parts to be hereinafter described and claimed.

In the accompanying drawing,

Fig. 1 is a fragmentary front elevation 75 of an index or file embodying my improvement.

Fig. 2 is an enlarged detail section 80 through the lower edge portions of several cards on line 2—2 of Fig. 1.

Fig. 3 is a front view of the lower part 85 of a card, and

Fig. 4 is a rear view of the lower part of a card.

As previously stated, the cards or record 85 members selected for illustration are of the downhanging or pendant type. In some features they are similar to the upstanding cards shown in my Patent No. 1,223,168, dated April 17th, 1917. A plurality of cards 90 5 are adapted to be mounted in a predetermined overlapped relation by means of tongues near the upper edges of the cards, adapted to engage a supporting strip 6 mounted on a carrier leaf 7, the lower edges 95 of the cards being free and exposed. The lower edge portion of each card extends downwardly below the card next in front of the same to a certain definite extent, as shown at 8 in Fig. 2. The exposed portion 100 of each card is protected by transparent means carried by the card next in front of the same. For this purpose I prefer to secure a strip 9, of celestron or other transparent material, along the lower portion of 105 each card, a part of such strip being applied

to the rear surface of the card by gluing, stitching or the like, and another part of the strip extending downward beyond the lower edge of the card proper, so as to cover and protect the exposed portion of the card at the rear of the first mentioned card. In this manner the exposed edge portions of the cards are protected from oil and similar substances on the hands of the person or persons using the index, but the visibility of the index is not impaired to any appreciable degree owing to the transparency of the protective strips. Any oil or like substance which may be deposited on the protective strips may be readily removed by wiping them with a damp cloth inasmuch as they are, of course, perfectly oil-proof and water-proof. Preferably, the celestron strips will be glued or stitched to the rear surfaces of the cards, and the downward extension of the strip beyond the lower edge of the card will correspond exactly with the overlap of the cards, so that the bottom edge of each transparent strip will be substantially flush with the bottom edge of the card proper, located behind said strip, as shown in Fig. 2. The addition of the transparent strips to the cards is a matter of small expense, and the strips do not interfere in any way with the separation of the cards for the interpolation of new cards or with such other manipulation as is usual in devices of this character. The protection of the record matter by celestron or the like can be achieved in accordance with my improved system at much less expense than is the case where it is necessary to provide each card with a special pocket for an insert. If desired, however, my improvements can be used advantageously in an index where plain cards are inserted between adjacent cards 5, and arranged so that their lower edges are exposed. In this case, the cards merely serve as holders, the record matter being carried by the interpolated cards or inserts.

It will be observed that by providing each card along its free edge with a transparent strip, the card is extended in area to a certain extent, and that the resulting record member is formed by a substantially opaque major portion, having a substantially transparent portion running along one of the horizontal margins. I do not, of course, limit myself in all aspects of the invention to a member composed of opaque and transparent portions which are secured together by an overlapping joint. Changes may be made in the details without departing from the scope of the invention.

I claim:

1. In an index or file, the combination of a support, and a plurality of cards mounted on said support in overlapped relation with one margin of each card exposed, each

card having a transparent portion overlapping the exposed margin of the card at the rear of the same.

2. In an index or file, a plurality of overlapped cards, and transparent portions secured to said cards, and extending beyond the free edges of the cards. 70

3. In an index or file, a plurality of cards, each card having one marginal portion extending beyond the card next in front of the same so as to be exposed, and a transparent protective portion on each card overlapping the exposed portion of the card at the rear of the same. 75

4. In an index or file, a plurality of overlapped flat record members, each comprising an opaque major portion, and a transparent marginal portion extending a substantial distance beyond the edge of the opaque major portion. 80

5. In an index or file, a plurality of overlapped flat record members, each comprising an opaque body portion, and a transparent marginal portion, the transparent marginal portion of each member overlying a part of the opaque portion of the member behind said first member. 85

6. In an index or file, the combination of a support, a plurality of cards mounted on said support in overlapped relation and having free edge portions carrying record matter, and transparent means upon each card for protecting the record matter upon an adjacent card. 90

7. In an index or file, the combination of a support, a plurality of cards mounted flatwise thereon, in overlapped relation, said cards having their edges exposed, and said exposed edges having record matter written thereon, and transparent means carried by each card for protecting the record matter on the card behind. 100

8. In an index or file, a plurality of cards arranged in overlapped relation with exposed edges, and a transparent portion upon each card extending beyond the exposed edge thereof. 110

9. In an index or file, the combination of a support, a plurality of downhanging cards mounted flatwise thereon in overlapped relation, and transparent strips on the lower edge portions of said cards extending below the lower edges of the respective cards. 115

10. In an index or file, a support, a card mounted flatwise thereon with one edge free, a second card similar to the first, mounted in front of the first but having a free edge so located relatively to that of the first card as to expose the marginal portion of the first card, and transparent means on said second card overlying said exposed marginal portion, said transparent means comprising a transparent strip applied to and overlapping the edge portion of the second card. 120

11. A flat record member for indexes or 130

files, having a transparent marginal portion positioned to permit record matter at the rear of said record member to be seen through said marginal portion.

5 12. A record member for indexes and the like, having means adjacent one margin for securing it to a support so as to leave the other margin free, such other margin being transparent.

10 13. A record card for indexes, having an edge portion adapted to contain record matter, and provided with a transparent extension beyond said edge portion.

15 14. A record card for indexes or files, having a transparent strip applied to one face thereof and extending beyond one edge of the card to protect record matter at the rear of said card.

20 15. A record card for indexes, having a transparent strip applied to the rear face thereof and extending beyond a horizontal edge of the card to protect record matter at the rear of said card.

25 16. A record card for indexes, having means adjacent one edge of the card for securing it on a support, and a transparent strip applied to the card adjacent its opposite edge and extending beyond said edge

to protect without concealing record matter at the rear of said card. 30

17. A record card for indexes, having means adjacent one edge of the card for securing it on a support, and a transparent strip secured to the card adjacent its opposite edge at the rear face of the card and extending beyond said edge to protect without concealing record matter at the rear of said card. 35

18. In an index or file, a plurality of overlapped flat record members, each comprising 40 an opaque portion and a transparent portion secured thereto, the transparent portion being positioned to protect without concealing record matter upon the record member behind said first member. 45

19. In an index or file, a plurality of overlapped flat record members having record matter upon the face thereof, and means for protecting without concealing said record matter comprising a transparent strip carried by the record member in front of the record matter which the strip protects. 50

In witness whereof, I have hereunto set my hand on the 30th day of July, 1917.

ROBERT D. HAYES.
